UNITED STATES PATENT OFFICE.

WILLIAM J. MADDOX, OF JAMESTOWN, NEW YORK.

SPINDLE SANDING MACHINE.

Application filed September 10, 1926. Serial No. 134,672.

This invention relates to improvements in wood working or finishing machines and particularly to a machine commonly known in the industry as a spindle sander.

5 One object of the invention is to provide a spindle sanding machine of comparatively simple construction whereby it may be produced at a minimum cost.

10 A further object is to provide the machine with an exceedingly simple arrangement for permitting oscillation of the work supporting table with respect to the sanding spindle.

15 Another object contemplated is the provision of a novel and inexpensive arrangement for adjusting the work supporting table longitudinally of the spindle roller in order that work on the table may be caused to engage different portions of the spool 20 or sanding spindle. In this way the operator can utilize first one portion of the spool or spindle and then another portion, and so on, until the entire surface of the spool has been utilized and its 25 abrasive surface worn out throughout its entire length.

With these and other objects in view the invention consists in certain novel details of construction and combinations and arrangements of parts, all as will be hereinafter 30 more fully described, and the novel features thereof particularly pointed out in the appended claims.

In the accompanying drawings:

35 Figure 1 is a side elevational view of the machine.

Fig. 2 is a sectional view of the opposite side of the machine.

Fig. 3 is a like view taken from the front 40 of the machine.

Fig. 4 is a like view taken from the rear of the machine, these several views showing the work supporting table in different positions.

45 Fig. 5 is a top plan view.

Fig. 6 is a transverse sectional view taken on the line 6—6 of Fig. 2.

Fig. 7 is a detail sectional view taken longitudinally of the sanding spindle or 50 roll.

Fig. 8 is a plan view of the dust removing fan attachment.

The machine comprises a frame or pedestal 10 adapted to be secured at its base by 55 suitable securing elements, and for purposes which will hereinafter appear the said

pedestal is preferably formed of a casting of U-shaped cross section. The work supporting table 11, the spindle sanding roll or spool 12 and the motor 13 for rotating 60 said spindle are all carried by said pedestal 10, the spindle being preferably maintained in an upright or vertical position so positioned with respect to the work supporting table that an article to be sanded may be 65 laid upon said table and its edge to be dressed or finished- pressed against the spindle.

In order that the table 11 may be oscillated with respect to the spindle 12, said table 70 is preferably carried by a pair of brackets 14 which, in turn, are pivotally secured to the ends of levers pivoted on pedestal 10. Preferably there is an upper lever 15 and a lower lever 16 at each side of the machine, 75 the table brackets 14 being secured at the forward ends of said levers. As will be apparent the brackets 14 together with the table 11 may be moved up and down by moving the levers 15, 16 on their centers at 80 the points at which they are pivoted on the pedestal. In order to maintain the table 11 in its proper working position with respect to the spindle 12 one set of the bracket supporting levers, preferably the 85 lower levers 16, are provided at their rear ends with counterweights 17 and to further aid in holding the table in its proper position, but in such manner that it may be so maintained yieldingly, the upper levers 15 90 have attached thereto at their rear ends springs 18 which are also attached to the rear portion of the pedestal 10. If an edge of an article is to be sanded and said edge forms a right angle with the surface of said article the surface of the work supporting table should lie at right angles to the sanding surface of spindle 12. On the other hand if the article has a beveled edge it is necessary that the angular position of the 100 table surface with respect to the spindle be changed. For this reason the table is pivoted to the brackets 14 and has a slot 19 therein through which extends a clamping screw 20 engaging the brackets whereby 105 the angular relation of the table and spindle can be varied. It will be noted that the table is shown in a tilted position in Figure 1 and in a horizontal position in Figure 2.

The present invention also contemplates 110 provision for adjusting the spindle longitudinally of its center of rotation in order

that it may project above the table any desired distance whereby any portion of its abrading surface throughout its length may be utilized thus permitting the entire surface to be worn out before the spindle is discarded. With this end in view the spindle 12 is slidably supported from the pedestal 10 and in the preferred construction the motor 13 for rotating said spindle is mounted on a supporting plate 21 vertically 10 slideable on the pedestal. Spindle 12 is attached to the upper end of the shaft 13^a of the motor and by adjusting plate 21 vertically of the pedestal the spindle itself may be projected any desired distance above the work supporting surface of table 11. To illustrate this the spindle is shown extending only partially above the table in Fig. 1, while the entire spindle is shown located 20 above the table in Fig. 2.

For adjusting the motor supporting plate 21 and spindle vertically there is pivoted on the pedestal 10 a lever 22 preferably of U-shape form, the arms of which are attached by connecting rods 23 to said plate whereby the operator may elevate or depress the plate by means of said lever. To hold the lever and the motor supporting plate 21 in any desired adjusting position suitable 30 means may be provided for supporting the lever 22. In the present instance these means are shown as consisting of a series of recesses 24 in the pedestal 10 and a pin 25 which is adapted to be inserted in any one 35 of the recesses so that it may support one arm of the lever.

For centering the upper end of the spindle there is mounted on the pedestal a post 26 having an adjustable collar 27 and said collar is formed with an arm 28 in the end of which there is threaded a centering screw 29, the point at the lower end of said screw being adapted to enter a central bore in the end of the spindle. When it is desired to raise or lower the spindle by movement of the lever 22 collar 27 is loosened so that it may slide freely on post 26 and after the spindle has been adjusted said collar is again tightened. This arrangement also 40 permits the spindle to be easily placed in or removed from the machine. As shown in Fig. 7 the end of the spindle which is inserted on the shaft 13^a of the motor has a tapered central bore 30 corresponding to the 45 similarly tapered end of said shaft and said shaft carries a cross pin 31 which is received in a transverse slot 32 in the end of the spindle whereby rotary motion to the shaft will be imparted to the spindle. When the 50 spindle or roll is to be inserted in the machine collar 27 and arm 28 may be turned to one side, the spindle or roll placed firmly on the tapered end of the shaft 13^a and then arm 28 turned back until the centering screw 55 29 is aligned with the central bore in the up-

per end of the roller spindle. The centering screw is then turned down into the spindle end and the collar 27 clamped on post 26. A further description of the spindle or roll 60 is deemed unnecessary as the same constitutes the subject matter of a copending application.

In machines of the present type the sanding spindle or roll runs at such a high speed 70 that it produces an exceedingly fine dust, the particles being as minute as those of flour and where it is desirable to have the machine of the portable type or where it is used in a factory not provided with a dust collecting system; it is essential that means 75 be provided for collecting the dust created by the machine. For this reason the present machine is provided with a fan 33 mounted on the shaft 13^a and enclosed within a housing 34 immediately beneath the 80 spindle or roll 12. The upper surface of the fan housing 34 has a multiplicity of openings therein whereby the particles of dust created by the abrading surface of the spindle will be sucked through the openings 85 in the housing top and blown into a receiving reservoir or receptacle which may take the form of a dust collecting bag 35 located between the rearwardly extending side portions of the pedestal 10. 90

What I claim is:

1. In a sanding machine, the combination of a frame or pedestal, levers pivoted on said pedestal, a work table carried by said levers, a sanding spindle, means for yieldingly maintaining said table in proper operative association with said spindle and means for adjusting said table to vary the angularity of the work-supporting surface thereof with respect to the spindle. 100

2. In a sanding machine, the combination of a frame or pedestal, a rotatable spindle, a work supporting table carried by said pedestal, means for yieldingly maintaining the table in proper operative association with said spindle, and means for adjusting said table to vary the angularity of the work supporting surface thereof with respect to the spindle. 110

3. In a sanding machine, the combination of a frame or pedestal, a rotatable spindle, a work supporting table carried by said pedestal, means for yieldingly maintaining the table in proper operative association with said spindle, means for adjusting said table to vary the angularity of the work supporting surface thereof with respect to the spindle, and means for moving the spindle longitudinally of its center of rotation. 115

4. In a sanding machine, the combination of a frame or pedestal, a work table supported on said pedestal, a motor, a sanding spindle mounted on the shaft of said motor and operatively associated with said work table, means for moving said spindle longitudinally of its center of rotation. 125

tudinally of its center of rotation, and means for releasably locking said spindle in any of its adjusted positions.

5. In a sanding machine, the combination of a frame or pedestal, a work table supported on said pedestal, a motor, a sanding spindle mounted on the shaft of said motor

and operatively associated with said work table, a support for said motor slidably carried by said pedestal, and a lever connected to the motor support for sliding the same on the pedestal and adjusting the spindle longitudinally of its center of rotation. 10

WILLIAM J. MADDOX.
